UNITED STATES PATENT OFFICE.

WILLIAM P. CUNNINGHAM, OF NORRISTOWN, PENNSYLVANIA.

APPARATUS AND PROCESS FOR CASTING CHAIN-LINKS.

1,295,702.

Specification of Letters Patent. Patented Feb. 25, 1919.

Application filed July 9, 1918. Serial No. 244,034.

To all whom it may concern:

Be it known that I, WILLIAM P. CUNNINGHAM, a citizen of the United States, and a resident of Norristown, county of 5 Montgomery, State of Pennsylvania, have invented certain Improvements in Apparatus and Processes for Casting Chain-Links, of which the following is a specification.

One object of my invention is to improve 10 the method of making chains of the type known as anchor chains, in which there is a web extending across each link at the center, but it will be understood that the invention can also be used in the manufacture of ordinary link chains.

A further object of the invention is to dispense with intricate molds in the manufacture of the chain and to make a pattern in such a manner that it can be readily drawn 15 from a one-part mold.

A still further object of the invention is to make a single pattern which will form a quarter section of a chain in such manner that molds made from a single pattern can 5 be arranged side by side so as to form a continuous mold for a chain.

In the accompanying drawings:

Figure 1 is a plan view of the flask, showing the pattern in position;

0 Fig. 2 is a sectional view on the line 2—2, Fig. 1;

Fig. 3 is a sectional view on the line 3—3, Fig. 1;

Fig. 4 is a perspective view of one section 5 of the detachable pattern forming one-quarter of one of the links;

Fig. 5 is a detached perspective view of the other section of the detachable pattern;

Fig. 6 is a transverse sectional view 10 through the mold on the line similar to that of Fig. 2, the pattern being removed;

Fig. 7 is a sectional view on the line 7—7, Fig. 6; the section being similar to that illustrated in Fig. 3;

Fig. 8 is a longitudinal sectional view showing a series of molds assembled to make a continuous chain;

Fig. 9 is a sectional view on the line 9—9, Fig. 8;

Fig. 9^a is a perspective view of the assembled sections; and

Fig. 10 is a side view of a section of the cast chain.

Referring to the drawings, 1 is the bottom board to which is secured the pattern 2, which is one-quarter of one of the links to

be cast. 3 is the flask and 4 is one-quarter of the pattern of one of the other links of the chain to be cast. The pattern is made in two parts 5 and 6. The part 5 is the 60 curved section forming one-half of one end of the link and this section has a projecting pin 7 which enters a hole in the bottom board 1 so as to retain this portion of the pattern in place. The other section 6 of the 65 pattern 4 has a portion 8, which is one-quarter of the pattern of the connecting web, which is present in substantially all anchor chains. This section has a perforation 9 and the section 5 is perforated at 10 in line with 70 the perforations 9 for the reception of a pin 11, which extends through the wall of the flask 3, through the section 6 and into the section 5, as clearly shown in Fig. 3. This arrangement retains the pattern in place 75 while the sand is being rammed around it.

14 and 15 are the patterns for the gates and 13 is a triangular piece set in the mold forming the flat upper surface of the mold when in position for pouring, as in Fig. 9. 80 Pins 14^a and 15^a retain the patterns 14 and 15 in place and these pins can be located in the holes in the flask 3, or in the opposite holes, as shown in Fig. 2, when it is desired to shift the patterns for the gates. The pattern 2, as hereinbefore stated, forms one-quarter of one of the links and has a portion 12 forming one-quarter of the web extending between the side members of the link. When the patterns are assembled, as in Figs. 85 1, 2 and 3, the sand is rammed around the several patterns, including the gate patterns 14 and 15, and when the patterns are withdrawn from the formed mold, the mold is as 90 illustrated in Figs. 6 and 7. Then these several quarter molds are assembled, as in Figs. 8 and 9, with the pouring openings or gates in the vertical position and the molds are arranged alternately side by side, the parting line of the molds being alternately on 100 planes at angles of 45 degrees to the horizontal, as clearly shown in Fig. 9. The molds are suitably supported in this position by a casing, or box, and the header connecting the several gates, as shown in Fig. 10, may be made in any ordinary manner.

When the molten metal is poured into the header it flows from the several gates and into the mold cavities, producing a continuous series of enchain links, as clearly 110 shown in Fig. 10. The gates are broken off of the links and the chains finished.

It will be understood that in making the molds, the gate patterns 14 and 15 will only be used on one-half of the series of molds, viz., the upper half. In making the molds for the lower series, the gate patterns are omitted, making the mold as clearly shown in Fig. 9.

I claim:

1. The combination in apparatus for casting chain links, of a flask; a bottom board; a half section of a portion of a link pattern secured to the said board; a pattern of a quarter section of a link mounted vertically and made in two parts; means for securing the parts together and to the flask so that when the sand is rammed around the pattern and the pattern is withdrawn a mold for a section of enchain links is formed and when a series of these mold sections is arranged side by side a mold for a complete series of enchain links is formed so that when the metal is poured a continuous chain is produced.
2. The combination in apparatus for casting chain links, of a flask; a bottom board; a quarter section of a link pattern secured to the bottom board; a quarter section of another link pattern arranged at right angles to the first mentioned section and located in the flask, said last mentioned quarter section being made in two parts; and means for securing said parts together and to the flask so that when the sand is rammed around the patterns in the flask and the flask and the bottom board are removed, the two parts of the pattern can be withdrawn from the mold, one in one direction, and the other in the opposite direction.
3. The combination in apparatus for making anchor chains, in which each link has a cross bar at the center, of a flask; a bottom board; a quarter pattern of a link having a quarter section of a cross bar formed thereon; a complete pattern of another quarter section of a link; a quarter section of another pattern of a link arranged at right angles to the other pattern and extending into the space between the end of the link and the cross bar, said pattern also having a quarter section of a cross bar, the latter pattern being made in two parts; and means for coupling the two parts together and to the flask, the part with the quarter section of the cross bar terminating at the flask, while the other section terminates at the bottom board so that when the sand is rammed around the patterns and the flask and the bottom board are removed, the two-part pattern for one of the link portions can be removed by withdrawing it laterally from the sand and the other by turning it in the sand, producing a section of a mold which, when assembled with the other sections, forms a complete pattern for a continuous chain.

4. The combination in apparatus for casting enchain links, in which each link has a cross bar, of a flask having a bottom board; a quarter section of a link pattern secured to the bottom board; a vertically arranged two-part quarter section of a link extending over a portion of the link pattern on the bottom board; means for securing the two portions together and to the flask, one part being curved in the segment of a circle and the other part having a portion of a cross bar pattern thereon, the last mentioned piece being tapered and the segmental piece having a pin extending into an opening in the bottom board so as to steady said section and when the sand is rammed in the flask and around the pattern, and when the flask and the bottom board are removed the two-part pattern can be withdrawn by turning the curved part of the mold up and withdrawing the other part laterally from the mold.

5. The combination in apparatus for casting enchain links, of a flask; a bottom board; a quarter section of a link pattern secured to the bottom board; a quarter section of another link pattern projecting at right angles from the first mentioned pattern and consisting of a curved and a straight section, the curved section extending over the first mentioned pattern; two gate patterns connected to the two patterns in the flask and extending at an angle to a triangular connecting pattern so arranged that when the mold is made, one half of the molds are made without the gate section and the other half with the gate section so that when the sections are assembled to form a continuous mold for the enchain links, they are arranged at an angle with the gates uppermost to enable the metal to be poured into each link cavity.

6. The process herein described of manufacturing a continuous chain, said process consisting in forming quarter molds for the links of the chain, arranging the quarter molds side by side with the link cavities at angles of forty-five degrees to the horizontal, one-half of the mold sections having gates arranged substantially in a vertical position, then pouring metal into the molds, and finally removing the sand in the molds, leaving a series of enchain links.

7. The process herein described of making a continuous chain, said process consisting in making two series of quarter section molds, one without gates and the other section with two gates, arranging the sections face to face and alternating the position of the pairs of molds so that all of the gates will be substantially in a vertical position, while the mold cavities for the links will be substantially at right angles.

8. The process herein described of manufacturing a continuous chain, said process consisting in forming a series of molds, each

having two cavities at right angles, one to the other, each cavity being for a quarter of a chain link, arranging the quarter molds side by side without individual flasks so that, when they are assembled, a series of cavities will be formed for complete en-chained links, with the exception of the two

end sections, then progressively pouring the metal into the molds thus formed, and continuing the pouring until the desired length 10 of chain is attained.

In witness whereof I affix my signature.

WILLIAM P. CUNNINGHAM.
